(57) **CLAIM**

The ornamental design for a clip with post and finger tabs, as shown and described.

DESCRIPTION

FIG. 1 is a top, rear, left side perspective view of our new design for a clip with post and finger tabs;

FIG. 2 is a top, front, left side perspective view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a rear elevation view thereof; and

FIG. 8 is a front elevation view thereof;

FIG. 9 illustrates a rear elevation view of the clip with post and finger tabs in an environment where coupled to a crutch;

FIG. 10 is a right side elevation thereof; and,

FIG. 11 is a top plan view thereof.

The broken lines in the drawings are included for the purpose of illustrating use and environment and form no part of the claimed design.

1 Claim, 11 Drawing Sheets
